(57) CLAIM

I claim the ornamental design for a desk fan, as shown and described.

DESCRIPTION

FIG. 1 is a front perspective view of the desk fan.

FIG. 2 is a front elevation view of the desk fan.

FIG. 3 is a rear view of the desk fan.

FIG. 4 is a side view of the left side of the desk fan.

FIG. 5 is a side view of the right side of the desk fan.

FIG. 6 is a plan view of the desk fan; and,

FIG. 7 is a bottom view of the desk fan.

The dashed lines in various figures are for illustrative purposes only and form no part of the claimed design.
